COMBINED TIE FOLDING AND SLIP STITCH
SEWING MACHINE

Carl W. Johnson, Brooklyn, and Joseph A. Neumair, Hollis, N. Y., assignors to American Machine & Foundry Co., a corporation of New Jersey

Application January 29, 1942, Serial No. 428,684

1 Claim. (Cl. 112—174)

This invention relates to a machine for making neckties and more particularly to assembling, folding and sewing together the necktie parts.

Necktie sewing machines in common use today, which are capable of inserting slip stitches, require the services of an operator to first fold the necktie materials into proper superimposed position by hand before commencing the sewing operation. In some cases a number of necktie materials are first pinned together in proper assembled relationship in one operation and are then sewn together in another completely distinct operation at a position remote from that where the fabrics were assembled. This procedure has been followed with the aim of cutting down the time consumed in folding necktie materials by hand as they are being sewn.

It is an object of the present invention to provide a unitary machine for assembling, folding and sewing necktie materials together with a slip stitch by a series of consecutive operations upon the tie fabrics while maintaining them at the same station in the machine throughout all of said operations.

Another object is to provide a simplified necktie making machine which will reduce the length of time and cost of making neckties by machine.

A further object is to provide a machine which will fold and sew necktie materials in one operation and in one position.

A further object is to secure a more accurate registration of folded necktie blanks and necktie linings with respect to one another and with respect to a needle inserting a slip stitch through said fabrics.

Other objects and features of the invention will appear as the description of the particular physical embodiment selected to illustrate the invention progresses.

In the accompanying drawings, which form a part of this specification, like characters of reference have been applied to corresponding parts throughout the several views which make up the drawings, in which:

Fig. 1 is a side view partially in section showing the pleating rack and the means for operating the sewing needle.

Fig. 2 is a diagrammatic end view of the necktie sewing needle.

Fig. 3 is a detailed end view showing the guiding and supporting structure for the sewing needle.

Fig. 4 is a cross sectional view showing the unfolded necktie blank and necktie lining positioned over the lower pleating rack and the folding plate.

Fig. 5 is a plan view showing the unfolded necktie blank and necktie lining, the lower pleating rack and the folding plates.

Fig. 6 is a cross sectional end view showing the folded necktie blank and necktie lining prior to the pleating operation and with the folding plates still in position.

Fig. 7 shows a necktie lining and necktie blank sewn together.

10 Referring to Fig. 1, the frame 10 supports a corrugated pleating bed 11. At one end of the pleating bed 11 are formed several corrugations 12 which are somewhat smaller in size than the corrugations 46 making up the rest of the pleating bed. A second pleating rack 13 is pivotally mounted on the frame 10 by means of arms 14 pivotally connected to lugs 15 by means of pivot pins 16. The lugs 15 are fixedly connected to the frame 10. A foot pedal 17 is also pivotally connected, by means of shaft 18, to the frame 10 of the machine, and by means of the connecting rod 47 imparts raising and lowering movement to the upper pleating rack 13. The spring 19 serves to hold the foot pedal 17 and upper pleating rack 13 normally in elevated position and yields under the foot pressure of an operator to permit the upper pleating rack to be pulled down upon the lower pleating rack, and by coaction of the corrugations 46 with corrugations 48 pleat necktie materials positioned on the lower pleating rack. A slot 20 is formed across the corrugations of the lower and upper pleating racks 11 and 13 which is adapted and arranged to receive, guide and support a sewing needle 21. The sewing needle 21 is fixedly connected at one end to the sprocket chain 22. The endless sprocket chain 22 is carried by sprockets 23 and 24, which are fixedly mounted on shafts 29 and 28 respectively. Shafts 29 and 28 are freely mounted in a suitable bracket 25 fixedly secured to the frame 10. A crank arm 26 having a crank handle 27 is fixedly connected to the shaft 28 and serves, when actuated by the operator, to impart forwarding and retracting movement to the needle 21 by means of the sprocket chain 22. The upper run of the sprocket chain 22 is guided between support bars 53 and 54. The upper bar 53 has a longitudinal slot 55 for guiding and supporting the needle 21 as it is forwarded and retracted by the sprocket chain 22.

45 A needle guide 30 having a countersunk opening 31 receives and guides the needle 21 into slot 20 when the needle is forwarded by the operator. To facilitate positioning of the necktie lining and necktie blank with respect to each other prior to folding, a lining guide 32 (Fig. 4) is provided.

50

adjacent to the lower pleating rack 11 so that the operator can place the edge 33 of the lining against the edge of the guide 32, guide 32 being secured to a plate 100 supported by frame 10. A slideable folding plate 34 has slide strips 35 fixedly connected thereto which are adapted to slide in slots 36 which are formed in the rectangular block 101 attached to the plate 102 secured to the top of frame 10 to restrict the plate 34 to a predetermined sliding path of travel. Adjustably secured to the plate 34 are necktie blank guides or gauge members 37 which have slots 38. A screw 39 passes through each of the slots 38 and is threaded into the plate 34. By loosening the screws 39, guide members 37 may be moved backward and forward and also turned about screw 39 so that they may be accommodated or adjusted to guide various shapes and sizes of necktie blanks.

A knob 40 is provided for the operator to move the holding plate 34 backward and forward to fold and hold the necktie blank. A back plate 41 is provided for holding the necktie blank in position with respect to the lining blank prior to the folding operation. The folding edge 42 of back plate 41 is shaped to impart the proper folding line to the necktie blank N and lining guide.

Extensions 49 of the plate 41 are pivotally mounted in rectangular sliding blocks 50 which are adapted to slide in conventional slide-ways formed in the inner lateral faces of members 51. The members 51 are secured to the plate 100. Suitable torsion springs 52 are provided to press the plate 41 downwardly and thereby impart a clamping action to back plate 41 when it is placed over the lining and necktie blank. Back plate 41 is pulled forwardly over the lining and necktie blank while at a slightly elevated angle and is withdrawn after the folding operation along a horizontal path of travel to avoid disturbing the necktie fabrics.

The operation of the machine may be briefly described as follows: With the upper plate rack 13 in elevated position, the folding plate 34 and back plate 41 in withdrawn position, and the needle 21 in retracted position, an operator places an unsewn lining blank over the lower pleating rack 11 so that the edge 33 of the lining is positioned against the fixed lining gauge 32. The operator then positions the outer edge of the necktie blank N against the guides 37 and lays the rest of the necktie blank over the lining L already positioned over the pleating rack 11 with its edge abutting guide plate 32 as shown in Fig. 4. The operator now grasps back plate 41, holding it in raised position, and moves it forward, placing it down over the lining L and necktie blank N so that the edge 42 thereof is placed where the fold line of the necktie blank is to be. The operator then grasps knob 40 and pushes the folding plate 34 forward in the direction indicated by the arrow in Fig. 4 to fold the necktie blank along the fold line formed by edge 42.

After this operation, the operator withdraws back plate 41, leaving folding plate 34 holding

the folded necktie blank and lining in overlapped and superimposed position. Next, the operator steps on the foot pedal 17, bringing down upper pleating rack 13 upon lower pleating rack 11 so as to pleat the overlapped and positioned necktie fabrics. Then by means of crank handle 27, the operator forwards needle 21 through the pleated necktie fabrics to position 43, shown in Fig. 1, the thread T having been previously drawn from the spool supported on the holder 44 and passed through the guide 45 and threaded through the eye of the needle 21. The operator then takes hold of the free end of the thread and holds the same while retracting the needle by turning handle 27 in the opposite direction, thus leaving a thread in the pleated necktie materials. After the needle has been withdrawn, the thread is severed adjacent member 31 by suitable shears or a knife. At the completion of the sewing operation, the tie is turned inside out so that the necktie blank will be on the outside of the lining.

It is not always necessary to incorporate a necktie lining with a necktie blank and sometimes neckties are made without linings. Applicants' device can be used for making neckties either with or without linings without requiring any structural changes to be made in this machine.

The term "slip stitch," when used in this specification and claims, is intended to mean any conventional resilient stitch suitable for use in sewing necktie materials together which is capable of being stretched longitudinally.

The invention above described may be varied in construction within the scope of the claims, for the particular device selected to illustrate the invention is but one of many concrete embodiments of the same. The invention therefore is not to be restricted to the precise details of the structure shown and described.

40 What is claimed is:

45 In a sewing machine, the combination with means for supporting an outspread necktie lining and an outspread necktie fabric, said necktie fabric and lining being associated in superimposed relationship with each other with one longitudinal edge of said necktie fabric extending along a longitudinal axis of said lining, of mechanism for folding the fabric on said means to lap one of its longitudinal edges upon the edge thereof arranged to extend along a longitudinal axis of said lining, said means including a member having a corrugated face adapted to support the lining and folded fabric, a device having a corrugated face coacting with the corrugated face of said member to pleat and hold the lining and folded fabric supported on said member in pleated condition, a needle adapted to be passed through the pleated fabric and lining while held by said member and device to stitch the same together, and mechanism for operating said needle while said fabric and lining are held in pleated condition, to stitch the pleated fabric and lining together.

CARL W. JOHNSON,
JOSEPH A. NEUMAIR.
